UNITED STATES PATENT OFFICE.

JOSEPH EMILE WAGEMANS AND GUSTAVE LEDEWYN, OF BRUSSELS, BELGIUM.

STOP MECHANISM FOR ROTARY BOX LOOMS.

Application filed June 8, 1914. Serial No. 843,856.

(GRANTED UNDER THE PROVISIONS OF THE ACT OF MARCH 3, 1921, 41 STAT. L., 1313.)

To all whom it may concern:

Be it known that we, JOSEPH EMILE WAGEMANS and GUSTAVE LEDEWYN, subjects of the King of Belgium, residing at Brussels, Belgium, have invented new and useful Improvements in Stop Mechanism for Rotary Box Looms, of which the following is a specification.

In looms as hitherto constructed and more particularly in the looms known as rotary box looms, the loom is stopped automatically when a weft thread breaks or when a cop is exhausted by the direct action of the fork carrier upon the clutch lever.

15 The present invention has for its object improvements enabling the loom to be run continuously and without stoppage when a weft thread breaks or a cop is exhausted and to bring the following shuttle automatically into operative position relatively to the warp.

20 A further object of the invention is a device for regulating the action of the regulator when a weft thread breaks or a cop is exhausted in such a manner that the loom rotates idly until the following shuttle has been brought into the operative position in order to avoid missed wefts or faults in the fabric.

25 Another object of the invention consists in automatically stopping the loom when all the shuttles have operated, the operator being unable to restart the loom until the barrel has been recharged.

30 The invention is illustrated in the accompanying drawings, in which:-

Figure 1 is a diagrammatic front elevation of a loom embodying the present improvements.

35 Figure 2 is a corresponding plan.

Figure 3 is a side elevation of the loom viewed from the left hand side of Figures 1 and 2.

40 Figure 4 is a similar view from the right hand side.

1 designates the frame of the loom.

In weft replenishing looms as ordinarily constructed, the fork carrier 2 carries the fork 3, and when a weft thread breaks or a cop is exhausted, the latter engages a hammer 4, which is given an oscillating movement by the action of an eccentric 48 mounted on a driving shaft 49. This causes the carrier to actuate a bar 6, and thereby operate a clutch lever 5.

In the improved loom which forms the object of the present invention, the bar 6 is given a special form (see Figure 2) and no longer influences the clutch lever 5 when it is rocked about its pivot 7. Here the oscillations of the bar 6 serve to cause the free extremities of two levers 8 and 9 to oscillate; of these levers, 8 is fixed at its lower end to a rod 10 passing along the whole side of the loom and journalled in the two extreme uprights of the frame, while the other lever 9 is fixed by its lower end to a rod 11 parallel with the rod 10 and also journalled in the two lateral uprights of the loom.

On the left hand side of the loom upon the rod 10 a lever 12 is fixed; this lever is lifted by the rotation of the rod 10 produced by the oscillation of the lever 8 and will lift the retaining pawl of the usual regulator 13 and prevent the winding of the warp of the fabric when the device described has functioned as a result of the breakage of the weft thread or the exhaustion of a cop, causing the fork carrier 2 to act. The object of this arrangement is to prevent missed wefts or faults as will readily be understood.

To the left hand end of the rod 11 one of the arms of a bent lever 14 is fixed, the free end 15 of its other arm bearing against the upper extremity of a lever 16 when the rod 11 rotates; this lever 16 is pivoted at 17 at its lower end and is normally drawn towards the front of the loom by a tension spring 18. The upper end of this lever 16 ends in a hook 19. Upon a fixed part of the frame 1, one end of a lever 20 is pivoted at 21 while its other free end carries a catch 22. By means of a roller 23 this rod 21 rests on a cam 24 mounted at the extremity of the driving shaft 49 of the loom. In its continuous rotation, this shaft 49 periodically lifts the rod 20. Normally when the rod 20 is lifted, its catch 22 does not engage the hook 19 on the lever 16 but when the rod 11 has been rotated by the action of the fork carrier 2 when a weft thread has broken or a cop has become exhausted, this rod 11 will press the bent lever 14 whose end 15 will bear against the hook 19 to cause the latter to engage the catch 22 in opposition to the action of the spring 18. The rod 20 being then lifted by the cam 24, the link 16 will also be lifted.

One end of a two-armed lever 25 is jointed to the lower end of this link 16; this lever 25 is pivoted at 26 and its other extremity 110

is normally maintained raised by a tension spring 27 attached to a fixed portion of the frame. The lower end of a rod 28 is jointed to the raised extremity of the lever arm 25; 5 this rod 28 is suitably guided and its upper extremity carries a hook 29. When the extremity of the lever 25 is depressed in opposition to the action of the spring 27 by the lifting of the hook 19 engaging the catch 10 22 as explained above, this hook 29 engages a tooth of a wheel 30 integral with the shuttle barrel 31 and causes this wheel to rotate to the extent of one tooth in such a manner that a fresh shuttle is presented and driven 15 into the shed to continue the weaving. The constructional form of the wheel 30 and of the barrel 31 is generally known and does not need a more detailed description.

From what has been stated it will be seen 20 that when a weft thread breaks or a cop is exhausted, the following shuttle will be brought automatically to the operative position and driven into the shed and that during the short space of time necessitated for 25 these automatic operations, the regulator will prevent any weft threads from being missed in the fabric by the momentary stoppage of the warp upon the yarn beam. As soon as a fresh shuttle has been projected 30 into the shed, the fork 3 will be lifted and no longer displaced by the hammer 4 in such a manner that the rods 10 and 11 will no longer be actuated and that all the active 35 parts described will resume their normal position of repose until a fresh breakage occurs or the recharging of a shuttle is rendered necessary by the exhaustion of the cop in action.

The mechanism which serves automatically to stop the loom when all the shuttles 40 have acted, that is to say when the barrel is to be recharged, is as follows:

Upon the wheel 30 of the barrel a pin 31' is provided at a suitable place and when the 45 said wheel 30 has effected a complete revolution, this pin engages a hook 32 in which a suitably guided link 33 ends; the lower end of this lever is pivoted to one extremity of an arm 34 whose other end is keyed upon 50 a shaft 35 extending throughout the entire side of the loom and suitably journaled in the lower part of the lateral uprights of the loom. When the operator has fully charged the barrel, he arranges it in such a 55 manner that the pin 31' comes immediately above the hook 32 so that this hook will only engage the pin when all the shuttles have acted, that is to say when the barrel has effected a complete revolution. When the link 60 28 has brought all the shuttles into action in succession, the pin 31' will encounter the hook 32 which will be lifted and cause the shaft 35 to rotate.

Upon the right hand end of this shaft 35 65 a short link 36 is fixed and at the other end

of this link, the lower end of an upwardly directed rod 37 is journalled; the upper end of this rod presents a fork 38 (see Figures 2 and 4). The free extremity of a rocking arm 39 pivoted to the clutch lever 5 of the loom rests in this fork. When the lever 37 is lifted by the rotation of the shaft 35 produced by the engagement of the hook 32 with the pin 31', this arm 39 will also be lifted and its free end will thus encounter the batten 40 (Figure 4) or an appropriate stop 41 fixed upon the batten. The blow produced by the batten on the extremity of the arm 39 will declutch the operating lever 5 upon which this arm is mounted and the loom will automatically stop. 75 80

When the loom has stopped, the operator cannot release the clutch lever until the barrel has been re-charged, as otherwise the pin 31 will maintain the hook 32 raised, so that the operating lever is in the declutched position. 85

In looms as hitherto constructed, if for example, the operator should inadvertently project into the shed a shuttle without a weft the loom would stop automatically. With the device described above, the loom would not be stopped, but would continue to rotate in actuating the hook 29 which would automatically render a fresh shuttle operative and so on in succession until a full shuttle has been projected onto the shed. 90 95

During this change of shuttle, that is to say until the moment at which a shuttle provided with thread has been driven into the shed, the warp of the fabric is not wound owing to the action of the regulator 13 as already explained. It follows that the loom acts automatically and without producing the least fault in the fabric so long as the barrel contains a shuttle ready to act, the loom being automatically stopped only when all the shuttles of the barrel have been driven into the shed. The work of the operator is therefore greatly reduced. 100 105 110

When the barrel is being recharged the end of the thread of each cop is attached by the operator to a knob or projection on a fixed portion of the frame in proximity to the barrel in order to cause the cop to unwind when the shuttle is driven. 115

It should be understood that the invention described above is in no way limited to the embodiment here described by way of example and diagrammatically illustrated 120 in the drawings, as numerous modifications might be introduced into the forms, proportions and methods of actuating the several elements without departing from the principle of the invention. 125

We claim:

1. In a loom, the combination of a lever mechanism, a rotatable shuttle barrel a stop on the shuttle barrel which actuates said lever mechanism when all the shuttles have 130

acted, an operating lever, connections between said lever mechanism and operating lever, to stop the loom for the purpose of recharging the barrel, said parts being arranged so that the operating lever can not again engage until the barrel has been recharged.

2. In a loom, a carrier actuated when a weft thread breaks or a cop is exhausted, a lever operated thereby, a rotatable shuttle barrel, means in connection with the lever for producing the rotation of the shuttle barrel, an operating lever for starting and stopping the loom, and means for actuating

the operating lever only when all of the 15 shuttles in the barrel have been used, said means comprising a projection rotatable with the barrel, a hook for engaging the projection, and a connection from the hook to the operating lever.

In testimony whereof we have signed our names to this specification in the presence of two subscribing witnesses.

JOSEPH EMILE WAGEMANS.
GUSTAVE LEDEWYN.
